TRIANGULAR TUBULAR MEMBER FOR SLIDABLY
SUPPORTING CLOTHING HOOKS AND SIMILAR
ARTICLES

Carl E. Gingher, 304-328 Depot St., Scranton, Pa.

Filed Sept. 11, 1964, Ser. No. 81,681

Term of patent 14 years

(Cl. D33—8)

FIGURE 1 is a perspective view taken from the end, top and side of a triangular tubular member for slidably supporting clothing hooks showing my new design;

FIGURE 2 is a perspective view taken from the end, bottom and side thereof; and

FIGURE 3 is a cross sectional view taken on line 3—3 of FIGURE 1.

The center portion of the member is broken away in FIGURES 1 and 2 to indicate indeterminate length.

The feature of my design resides in the planar bottom having guide members defining a track extending the length of the member as shown.

I claim:

The ornamental design for a triangular tubular member for slidably supporting clothing hooks and similar articles, as shown and described.
